UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

COMBINED SPRAYING AND SEAMING MACHINE.

1,206,423.

Specification of Letters Patent. Patented Nov. 28, 1916.

Application filed March 3, 1913. Serial No. 751,776.

To all whom it may concern:

Be it known that I, FELIX EBERHART, a citizen of the United States, residing in Newark, in the county of Essex and State 5 of New Jersey, have invented a new and useful Improvement in Combined Spraying and Seaming Machines, of which the following is a specification.

This invention relates to improvements in 10 machines for coating the interiors of cans and seaming the bodies and ends.

An object of the invention is to provide a single machine which will apply a coating of lacquer or other protective material 15 to the inner walls of a loosely assembled body and end, and which will also double seam the end to the body.

Another object of the invention is to provide a machine, automatic throughout, which 20 comprises means for feeding can ends one by one from a stack to a rotatable turret; means for feeding bodies automatically to the turret in position over the previously fed can ends; means for assembling the bodies and 25 ends; means for spraying or otherwise applying a coating of lacquer or equivalent protective material to the inner walls of the can body and ends, the coating material also being utilized to serve as a packing or seal 30 between the body and end flanges for the double seam; mechanism for seaming the ends and bodies together; and means for ejecting the articles from the turret after 35 all the foregoing operations have been completed.

Another object of the invention is to provide a machine of the type above indicated, which operates at high speed and is of relatively simple construction.

A still further object of the invention is 40 to combine in a single machine, means whereby a protective coating may be applied to the interior of the bodies and ends, the coating material being utilized to form the packing between the seam forming flanges.

The invention furthermore consists in the improvements in the parts and devices and in the novel combinations of parts and devices herein shown, described or claimed.

In practice, it has been found that many 45 food stuffs attack the tin and form salts of

tin, and to obviate this, it has been customary to lacquer or otherwise coat the interior of the cans, which has been done by two methods, one of which consists in forming the can bodies and ends from previously coated sheets of tin, and the other of which consists in coating the interior of the can after the body and end have been united. The first method of manufacturing internally lacquered cans has sometimes proved 55 objectionable, for the reason that the lacquer or other coating becomes scratched or marred during the formation of the can, which, of course, permits the acids to attack 60 the tin at the exposed parts. With the second method of forming the internally coated cans, a separate machine has been required to apply the lacquer or other coating, and, to which the can bodies are fed 65 after the double seaming operation. This last method, besides entailing the expense of two machines, also generally necessitates a separate handling of the cans between the seaming and lacquering operations, thereby 70 increasing the cost of labor.

With my improvements, I aim to provide a machine which will be free from all of the objections, above pointed out, resulting from the former methods of manufacturing 75 internally coated cans.

In the drawing forming a part of this specification, Figure 1 is a side elevation of one form of a machine embodying my improvements. Fig. 2 is a top plan view of the 80 structure shown in Fig. 1. Fig. 3 is a horizontal sectional view, taken substantially on the line 3—3 of Fig. 1, and being upon a somewhat larger scale than Fig. 1. Figs. 4 and 5 are vertical, sectional views taken 85 substantially on the lines 4—4 and 5—5 of Fig. 2, respectively, parts being broken away and omitted at the bottom of each of said figures. Fig. 6 is a horizontal, sectional view, taken on the line 6—6 of Fig. 1. Fig. 7 is a detail view of a portion of the cam track employed in the ejecting mechanism. Figs. 8 and 9 are horizontal, sectional views, 90 taken substantially on the lines 8—8 and 9—9, respectively, of Fig. 1, and Fig. 10 is 95 a detail sectional view, taken through one of the clutch heads.

In said drawing, the machine, as shown, comprises a main standard 10 and a secondary base or standard 11, the former having mounted therein a horizontal shaft 12, from which the various parts of the mechanism are driven, power being derived from any suitable source, not shown, through the fast and loose pulleys 13. Mounted in the base or standard 11 is a continuously 5 rotatable, vertical shaft 14, the latter being driven by means of a gear 15, keyed or otherwise secured thereto, the gear 15 being driven from another larger gear 16, secured to a vertical shaft 17, having a bevel gear 18 thereon, driven by means of another bevel gear 19, secured to the end of a horizontal shaft 20, said shaft 20 being driven from the shaft 12 through the intermediary of two gears 21 and 22. (See Figs. 3 and 8). 10 Mounted on the shaft 14 and independently rotatable thereon is a carrier in the form of a turret having a lower deck 23 and an upper deck 24, said decks being united by means of vertical connecting members 25, equally spaced around the peripheries of the same. Said carrier is given an intermittent rotation by means of a Geneva motion comprising a constantly rotating element 26 on the shaft 17, and the slotted gear 27 which is formed rigid with the lower deck 23. (See Figs. 4 and 8). The upper deck 24 of the carrier is provided with a plurality of holders in the form of chucks 28, mounted in chuck housings 128, each of said 20 30 35 40 45 50 55 60 65 70 75 80 85 90 95 100 105 110 115 120 125 130 chucks having a depending spindle 29, the latter being each provided at their lower ends with a clutch head 30, with which is adapted to engage a coöperating clutch head 31 formed rigid with a pinion 32, suitably mounted in a bearing 33 on the lower deck 23 of the carrier. The pinions 32, carrying the lower clutch heads 31, are constantly rotated by means of a major gear 34 keyed to the shaft 14, said gear 34, as more clearly shown in Fig. 4, being located intermediate the lower and upper decks 23 and 24. Each chuck is normally held in its lowermost position by means of a coiled spring 35 located within the chuck housing 128, and located within each chuck 28 is an ejecting disk 36, having a downwardly extending stem 37, mounted within the spindle 29, said ejector plate being operated, as hereinafter described, by means of a ring 38 secured to the stem 37 by means of a pin 39, which reciprocates up and down in a slot 40 formed in the spindle 29. At one point in the rotation of the carrier or turret, can ends are fed automatically one by one to the chucks of the carrier and seated in pockets 41 formed in the upper face of the carrier, and the means for feeding the can ends to the carrier comprises a reciprocating V-shaped slide 42, reciprocated by 65 means of a cam disk 43, having a cam groove

in which engages a roller on a pin 44 connected to the slide 42, the cam disk 43 being rotated by any suitable means, such as a sprocket gear 45, sprocket chain 46 and sprocket gear 47, the latter being secured to the upper end of the shaft 17. The slide 42 is provided with suitable means for separating the can ends one by one from a stack of can ends held in a stack holder 48, and each can end, as fed to the carrier, will be forced down into a pocket thereon by means of a spring 49, secured to the stack holder 48, the latter being in turn secured to an annular bracket 50, located above the carrier and secured to the standard 10, by suitable means, as shown in Fig. 1. Any desirable form of can end feeder may be employed, the one shown in the drawing being the same as that illustrated and described in the patent issued to Wegner & Peters No. 1,013,344, dated Jan. 2, 1912, to which reference may be had for a more detailed description of the can end feeder than is here given.

After a can end has been fed to the carrier and when the carrier has been given one forward movement in its rotation and again brought to rest, the can body is automatically fed to the carrier in position above the previously fed can end by means of a continuously traveling belt 51, supported on rollers and driven from any suitable source of power, the belt 51 forming the bottom of a can body guide having side and top ribs 52 and 53 secured to an upright 54, (See 100 Figs. 1 and 5), the upright 54 being also secured to the annular bracket 50. The bodies, as fed to the carrier or turret, will be properly centered by means of the segmental pockets 55, which are formed in the centering plate 56, secured to the upper deck 24 of the carrier, the pockets 55 being placed in alinement with the chucks 28 in a well known manner and, as will be obvious, the convex portions 57 of the plate 56 which are intermediate the pockets 55 will prevent the can bodies from being moved forward while the carrier is being intermittently moved.

At the next station after that at which the bodies are fed to the carrier, the can bodies and ends are pressed together and also simultaneously sprayed with lacquer or other equivalent protective coating material and I would have it understood that where the term "lacquer" is used in this application, I mean any material which may be used for covering or coating the interior walls of the can to protect the metal from being acted on by the acids of the food contents. At the spraying station during the spraying operation, the cans are given an axial, rotary movement by means of the pinions 32 and clutch heads 31 and 30, as hereinafter described. When a pinion 32 is moved by the carrier to a point beneath the 130

spray nozzle 58, the spindle 59 on which the pinion 32 is mounted, is brought in alignment with a lifting rod 60, slidably mounted in a bearing formed in a bracket 61, the latter being secured to the base 11. The lifting rod 60, after the carrier is brought to rest, is operated by means of a bell crank 62, pivotally mounted on the bracket 61, as at 63, and oscillated by means of a link 64 and bell crank 65, the latter having one end thereof engaging in a cam-groove 66 formed in the barrel cam 67, secured to a vertical shaft 68, driven by means of bevel gears 69, shaft 70, bevel gears 71 and 72, the latter being secured to the end of a horizontal shaft 73, having secured thereto at its opposite end a worm gear 74, driven by means of a worm 75, mounted on the horizontal shaft 20. When the lifting rod 60 is raised, it will move the stem 59 and pinion 32 carried thereby, so that the clutch heads 30 and 31 will engage each other, thereby rotating the chuck 28 and the upward movement will also raise the chuck 28 out of its recess in the chuck housing 128, and thereby press the can end and can body firmly together, due to the can body engaging at its upper end an annular, rotatable plate 76, mounted on the under side of the annular bracket 50 by means of a suitable ball bearing, as clearly shown in Fig. 4. The bracket 50 is provided with a hole 77, through which the spray nozzle 58 projects, so that the lacquer can be projected into the interior of the can, and in order to properly spray the interiors of the cans, the nozzle is provided with a lacquer supply pipe 78, connected with a supply tank (not shown) and a compressed air supply pipe 79, connected to any suitable source of compressed air (not shown), the supply of lacquer and compressed air to the nozzle being regulated and controlled by means of a pair of valves 80 simultaneously operated by means of a link 81, bell crank 82, having a spring controlled arm 83, connecting link 84 and bell crank lever 85, the latter being operated by means of a raised cam 86, formed on one of the seaming roller slides 87, said slide being operated by means hereinafter described. For regulating the jet or spray from the nozzle 58, the latter is provided with an adjustable, conical valve 88, which cooperates with a correspondingly shaped valve seat.

After the can bodies and ends have been assembled or pressed together and sprayed, as just described, the carrier or turret is given two more forward movements, whereupon the assembled can body and end are brought to the seaming station. (See Fig. 5). At this station, the chuck 28 will again be raised and rotated in the same manner as at the spraying and assembling station through the instrumentality of the lifting rod 39, mounted similarly to the lifting rod

60 and operated by means of a lever arm 165, operated simultaneously with the bell crank 65 (see Fig. 9), and which has a pin and slot engagement with the rod 89. At the seaming station, the can body will be raised 70 and pressed against an upper, rotatable chuck 90, mounted on the lower end of an adjustable spindle 91, which in turn is mounted in an overhanging bracket 92, formed integral with the standard 10. The 75 seam-forming flanges of the body and can end will be brought in line with the seaming rollers 93, mounted on the seaming roller slides 87, said seaming rollers being operated one after the other in the usual manner to 80 complete the double seam, the slides 87 being each reciprocated by means of a pivoted lever 94, pivotally connected to the slide and having a roller at its lower end engaging a cam 95 on the shaft 73, the slides being each 85 retracted by means of a suitable spring 96.

After the double seaming operation, the carrier is moved forward another step, and during this movement, the ring 38, which is pinned to the stem of the ejector plate, will 90 slide up over a stationary cam 97 (see Fig. 7), thereby lifting the ejector plate 36 and the now sprayed and seamed can, and during the next forward movement of the carrier, the can will be ejected from the carrier by 95 means of the ejecting finger 98 onto a guide-way or track 99 that directs the can bodies to a baking or curing oven (not shown). As the carrier is again moved forward, the ring 38 will slide under and be depressed by another stationary cam 100 (see Fig. 7) to thereby return the ejecting plate 36 to normal position, whereupon the carrier will be rotated to receive another can end when the chuck 28 is stopped opposite the can end 105 feeding mechanism.

From the foregoing description, it will be seen that during each period of rest of the carrier, five operations are occurring simultaneously, at different points spaced around the periphery of the carrier, namely, the feeding of a can end to one chuck, the feeding of a body to the carrier above a previously fed can end, the simultaneously assembling or pressing together of a can body 110 and end and spraying of the interior of the can at the station following the body feeding station, and the double seaming operation at another station. It will also be noted that all the operations are automatic 120 throughout, that the chucks 28 are rotated only at the spraying and seaming stations, and also that the spraying of the interior of the can is done before the body and end are seamed together, whereby the lacquer 125 or other coating material is permitted to flow between the seam-forming flanges to form the packing or sealing material in the double seam.

In order to prevent the cans from being 130

displaced during the rotation of the carrier, a guard rail 101 is provided which, as shown in the drawing, extends from the spraying station nearly to the seaming station.

5 Although I have herein shown and described in detail one form of machine embodying my improvements, yet it will be understood that the same may be changed and modified without departing from the 10 spirit of the invention, and all such changes and modifications are contemplated as come within the scope of the claims appended hereto.

I claim:—

15 1. A combined, protective coating applying and seaming machine comprising, in combination: means for applying a coating of protective material to the interior of an assembled flanged can body and can end;

20 mechanism for seaming the body and end together; and coöperating means for conveying the assembled can body and end from said applying means to the seaming mechanism, substantially as specified.

25 2. A machine of the character described comprising, in combination: means for assembling a can body and can end in juxtaposition for seaming; a device for applying a coating of lacquer or equivalent material to the interior of an assembled body and end; seaming mechanism for uniting the body and end; and coöperating means for conveying the assembled can body and end from the said coating device to the seaming mechanism, substantially as specified.

30 3. A combined, protective coating applying and seaming machine comprising, in combination: means for applying a coating of lacquer to the interior walls of an assembled, flanged can body and can end; double seaming mechanism for uniting the body and end; and coöperating means for conveying the assembled can body and end successively to the said coating means and

35 to the seaming mechanism, substantially as specified.

4. A machine of the character described comprising, in combination: means for assembling a flanged can body and can end in juxtaposition for double seaming; a lacquer spraying device for applying a coating of lacquer to the interior of the assembled body and end; and double seaming mechanism operating subsequently to said spraying device for uniting the body and end, substantially as specified.

5. A machine of the character described including, in combination: a movable carrier having a can holder thereon; means, located in operative position relatively to said carrier, for applying a coating of protective material to the walls of the can; and seaming mechanism operating subsequently to said applying means, arranged in operative position relatively to the carrier, for

uniting a can body and can end while on said carrier, substantially as specified.

6. A machine of the character described including, in combination: a movable carrier having a can holder thereon; means, 70 located in operative position relatively to said carrier, for applying a coating of protective material to the walls of the can; and seaming mechanism operating subsequently to said applying means, arranged in operative position relatively to the carrier, for uniting a can body and can end while on said carrier, said seaming mechanism being separated from the coating means and operating on the same can body and end at a 80 different time than the coating means, substantially as specified.

7. A machine of the character described including, in combination: a movable carrier having a can holder thereon; means, 85 located in operative position relatively to said carrier, for applying a coating of protective material to the walls of the can; seaming mechanism operating subsequently to said applying means, arranged in operative position relatively to the carrier, for uniting a can body and can end while on said carrier; and means for automatically feeding bodies and ends to the carrier, substantially as specified.

8. A machine of the character described including, in combination: a movable carrier having a holder thereon adapted to support and hold a can body and can end in juxtaposition for seaming; means for feeding can bodies and ends to the carrier; a device for applying a coating of protective material to the interior walls of an assembled can body and can end on the carrier; and seaming mechanism, operating subsequent to the coating device, for uniting the can body and end while on the carrier, substantially as specified.

9. A machine of the character described including, in combination: a movable carrier having a holder thereon adapted to support and retain a can body and can end in assembled position; a can end feeder for feeding ends to said holder; a can body feeder, the latter being spaced from the can end feeder; a device for applying a coating of protective material to the interior walls of an assembled can body and end; and seaming mechanism operating subsequently to said applying device for uniting the body and end, substantially as specified.

10. A machine of the character described including, in combination, a movable carrier having a holder thereon adapted to support and retain a can body and can end in assembled position; a can end feeder for feeding ends to said holder; a can body feeder, the latter being spaced from the can end feeder; a device for applying a coating of protective material to the interior walls

of an assembled can body and end; and seaming mechanism operating subsequently to said applying device for uniting the body and end, the seaming mechanism being spaced from the coating device, substantially as specified.

11. A machine of the character described including, in combination: a rotary carrier having a holder thereon; means for applying a coating of protective material to the interior of an assembled can body and end on said carrier; and seaming mechanism operating subsequently to said applying means for uniting the body and end while on said carrier, substantially as specified.

12. A machine of the character described including, in combination: a rotary carrier having a holder thereon adapted to support and retain an assembled can body and can end; means for spraying the interior walls of an assembled can body and end while on said carrier; and seaming mechanism operating subsequently to said spraying means for uniting the body and end, substantially as specified.

13. A machine of the character described including, in combination: a rotary carrier having a holder thereon; means for applying a coating of protective material to the interior of an assembled can body and end on said carrier; seaming mechanism operating subsequently to said applying means for uniting the body and end while on said carrier; and means for feeding bodies and ends to the rotary carrier, substantially as specified.

14. A machine of the character described including, in combination: a rotary carrier having a holder thereon; means for applying a coating of protective material to the interior of an assembled can body and end on said carrier; seaming mechanism operating subsequently to said applying means for uniting the body and end while on said carrier; a can end feeder; and a body feeder, the latter being located at a different point in the path of rotation of the carrier than the can end feeder, substantially as specified.

15. A machine of the character described including, in combination: a rotary carrier having devices thereon for holding and retaining an assembled can body and can end; means for feeding a can end to the carrier at one point in its rotation; a body feeder for feeding bodies to the carrier at another point in its rotation; a spraying device located adjacent the carrier and adapted to apply lacquer to the interior of an assembled can body and end; and seaming mechanism operating subsequently to said spraying device for uniting the body and end, substantially as specified.

16. A machine of the character described

including, in combination: a rotary carrier having means thereon for holding an assembled can body and end; means for feeding a can end and can body to said carrier; a stationary spraying device located above said carrier and adapted to apply lacquer to the interior of an assembled can body and end on the carrier; and relatively stationary seaming mechanism operating subsequently to said spraying device substantially as specified.

17. A machine of the character described including, in combination: a movable carrier having means thereon for holding a can body and can end in assembled position; means, stationary relatively to said carrier, for applying a coating of protective material to the interior of an assembled can body and end; and seaming mechanism operating subsequently to said applying means, stationary relatively to said carrier, for uniting the body and end, substantially as specified.

18. A machine of the character described including, in combination: a carrier rotatable about a vertical axis and having a plurality of can holders thereon; a stationary spraying device for applying lacquer to the interior of assembled can bodies and ends on the carrier; and seaming mechanism operating subsequently to said spraying device, stationary relatively to the carrier, for uniting the bodies and ends, substantially as specified.

19. A machine of the character described including, in combination: a carrier rotatable about a vertical axis and having a plurality of can holders thereon; means for applying a coating of protective material to the interiors of assembled can bodies and ends on said carrier; and seaming mechanism operating subsequently to said applying means for uniting the bodies and ends, substantially as specified.

20. A machine of the character described including, in combination: a carrier rotatable about a vertical axis and having a plurality of can holders thereon; means for applying a coating of protective material to the interiors of assembled can bodies and ends on said carrier; and seaming mechanism operating subsequently to said applying means for uniting the bodies and ends, the seaming mechanism being located adjacent the carrier at a different point than the spraying device, substantially as specified.

21. A machine of the character described comprising, in combination: a carrier rotatable about a vertical axis and having a plurality of can holders thereon; means for feeding can ends to said holders; means for feeding bodies to said holders and in position above said ends; a device for applying a coating of protective material to the in-

- ner walls of assembled can bodies and ends on said carrier; and double seaming mechanism operating subsequently to said applying device for uniting the bodies and ends, 5 substantially as specified.
22. A machine of the character described including, in combination: a carrier rotatable about a vertical axis and having a plurality of can holders thereon; a stationary 10 spraying device for applying lacquer to the interior of assembled can bodies and ends on the carrier; seaming mechanism operating subsequently to said spraying device, stationary relatively to the carrier, for uniting 15 the bodies and ends; and means for rotating the cans and spraying device relatively to each other during the pauses in the rotation of the carrier, substantially as specified.
23. A machine of the character described 20 including, in combination: a rotatable carrier having a plurality of axially rotatable chucks thereon; a spraying device adapted to spray assembled can bodies and ends while on said carrier; seaming mechanism operating 25 subsequently to said spraying device; and mechanism for rotating said chucks during the spraying and seaming operations; substantially as specified.
24. A machine of the character described 30 comprising, in combination: a rotatable carrier having a plurality of axially rotatable chucks thereon; means for feeding can bodies and ends to the chucks on said carrier; means for pressing the can bodies and 35 ends together after the same have been fed to the chucks; a spraying device for applying lacquer to the interior walls of assembled can bodies and ends on the carrier; seaming rolls operating subsequently to said 40 spraying device; and mechanism for rotating said chucks during the seaming operation, substantially as specified.
25. A machine of the character described including, in combination: a rotatable carrier 45 having a plurality of axially rotatable chucks thereon; means for feeding can bodies and ends to said chucks; means for pressing the can bodies and ends together after the same have been placed on the 50 chucks; a spraying device located above said carrier, the spraying device operating while the bodies and ends are being pressed together; and seaming mechanism operating 55 subsequently to said spraying device for uniting the bodies and ends, substantially as specified.
26. A machine of the character described including, in combination: an intermittently 60 rotatable carrier having a plurality of axially and independently rotatable chucks thereon, means for feeding can bodies and ends to the chucks while the carrier is stationary; spraying devices; seaming mechanism operating subsequently to said spray- 65
- ing devices; and means for rotating said chucks at the spraying and seaming stations, substantially as specified.
27. A machine of the character described including, in combination: a carrier rotatable about a vertical axis and having a plurality of chucks thereon; and a can end feeder, a can body feeder, a spraying device, and seaming mechanism operating subsequently to said spraying device, said can end feeder, body feeder, spraying device and 70 seaming mechanism all being operated simultaneously, substantially as specified.
28. A machine of the character described including, in combination: a carrier intermittently rotatable about a vertical axis and 75 having a plurality of independently, axially rotatable chucks thereon, said carrier having also a plurality of constantly rotatable pinions carried thereby, the number of said pinions corresponding to the number of chucks 80 and being in alinement therewith; co-operating clutch heads formed rigid with each chuck and pinion; a device for applying lacquer to the interiors of assembled can bodies and ends while on the chucks of said 85 carrier; and mechanism for moving said clutch heads together each time a chuck is brought beneath the spraying device, substantially as specified.
29. A machine of the character described 90 including, in combination: a carrier intermittently rotatable about a vertical axis and having a plurality of rotatable chucks and rotating pinions thereon, there being one pinion for each chuck; a spraying device located above said carrier beneath which the 95 chucks are adapted to be brought successively and held stationary; seaming mechanism adapted to unite the sprayed can bodies and ends while on said chucks when brought 100 into operative position with the seaming mechanism; and means for rotating said chucks from said rotating pinions when the chucks are in operative position relatively to the spraying device and seaming mechanism, 105 substantially as specified.
30. A machine of the character described including, in combination: an intermittently 110 rotatable carrier having a plurality of independently, axially rotatable chucks thereon; means for feeding can ends and can bodies to said carrier at different places and while the carrier is at rest; a lacquer spraying nozzle disposed above said carrier and in alinement with which the chucks are adapted to 115 be brought successively; seaming mechanism; and means for rotating the chucks successively as they are brought into operative position relatively to the spraying device and seaming mechanism, substantially as specified.
31. A machine of the character described including, in combination: a movable carrier

having a holder thereon adapted to support and hold a can body and can end in juxtaposition for seaming; means for feeding can bodies and ends to the carrier; a device for applying a coating of protective material to the interior walls of an assembled can body and can end on the carrier; and seaming

mechanism coöperating with the said carrier for uniting the can body and end while on the carrier; substantially as specified.

FELIX EBERHART.
